UNITED STATES PATENT OFFICE.

NEWCOMB CLEVELAND, OF NEW YORK, N. Y.

CAN-OPENER.

SPECIFICATION forming part of Letters Patent No. 727,905, dated May 12, 1903.

Application filed December 31, 1902. Serial No. 137,361. (No model.)

To all whom it may concern:

Be it known that I, NEWCOMB CLEVELAND, a citizen of the United States, and a resident of New York city, borough of Brooklyn, Kings county, State of New York, have invented a Can-Opener, of which the following is a specification.

This invention relates to devices for opening receptacles—such as boxes or cans containing shoe-polish, stove-polish, baking-powder, and other ingredients for which it is essential to provide a tight closure. The cover part of these receptacles is usually made with a very tight fit on the body portion, and often the contents of the receptacle is of such a nature as to act somewhat as a glue between the body and lid or cover. In such cases a direct upward push on the lid or its rim has generally been found quite inadequate to open the receptacle.

By my invention I provide a positively-operating lever-opener adapted to so coöperate with the box that the latter will act as the fulcrum-bearing and at the same time hold the lever in operative position until the box is opened—that is, the mere closure of the box secures the lever thereto.

In carrying out my invention I make the fulcrum and resistance points of my lever-opener bear one upon the body portion and one upon the cover of the receptacle, and preferably the lever is partly inclosed in the receptacle and partly projects therefrom, the outside part or handle being in a position for ready manipulation when it is desired to open the receptacle. The power applied to the handle of my improved device for opening the can is greatly multiplied at the resistance-point, as the device acts upon the principles of the lever and inclined plane or wedging action, as will be apparent.

In the accompanying drawings I have shown various forms of devices for putting my invention into practice; but I do not limit myself to any specific form or device beyond what is called for in the claims hereto appended.

Figure 1 is a side view of a box or can provided with a lever-opener made according to my invention. Fig. 2 is a perspective view of this opener drawn to a larger scale. Fig. 3 is a sectional elevation of a part of Fig. 1,

the section being taken on line 3 3. Fig. 4 is a side view of the box, representing the cover partially raised by the opener. Figs. 5, 6, and 7 are outside views of boxes provided with various modifications of my lever-opener, as hereinafter fully explained.

Referring to Figs. 1 to 4, the box, can, or other receptacle, of metal, cardboard, or any other desirable material, consists of a body *a* and a cover *b*. My lever-opener *C* in the construction here shown is formed with a handle *c'*, a portion *c²*, adapted to pass between the body *a* and cover *b*, and a portion *c³*, turned back over the rim of the body *a*, the part of the device joining the portion *c²* and the handle being turned out under the rim of the cover *b* at *c⁴*. It will be evident that when the box is closed, with the portion *c³* of the lever inclosed between the body *a* and cover *b*, the lever-opener will be firmly held in place with the handle *c'* outside the box. Preferably I form an offset in the receptacle, as shown, for instance, at *b'* in the cover *b*, in which offset the portion *c²* lies. When it is desired to open the box, the handle *c'* is simply pushed up or down. If the body *a* of the box is held in the hand, it may be assumed that the fulcrum of the lever bears on the rim of the body. Thus if the handle *c'* is pushed upward the lever will turn on the edge *x*, Figs. 2 and 4, and the portion *c⁴* under the rim of the cover *b* will raise the cover, Fig. 4, as it turns on the arc having *x* as a center. The power applied to the handle is increased at the resistance-point *y*, bearing against the rim of the cover *b*, according to the length of the handle, and this power at the resistance-point is also augmented by reason of the motion given it—that is, the point *y* of the lever does not exert its power in a line directly opposed to the resistance, but inclined thereto. Lever-opener *C* is represented as made of flat metal, while the levers shown in Figs. 5, 6, and 7 are shown as made of a strong wire or rod.

Fig. 5 represents a lever-opener consisting of a handle *c¹¹*, a portion *c¹²*, passing between the body *a* and cover *b*, this portion extending to the top of the inside of the cover, and a portion *c¹³*, turned downward to the bottom of the box. This portion *c¹³* is longer than the height of the inside of the receptacle, so

that when the receptacle is closed the portion c^{13} is in an oblique position, as shown. When the handle c^{11} is raised, the lever will tilt on one or the other of the points x' or y' , and as 5 the portion c^{13} assumes a position more nearly vertical with the height of the receptacle it will force the cover b from the body a .

Fig. 6 represents a lever-opener consisting of a handle c^{21} , a portion c^{22} , to be inclosed between the body a and the cover b , and a portion c^{23} , extending from the rim of the body a to the top of the inside of the cover b . The parts c^{22} and c^{23} are connected by a bend at x^2 resting on the rim of the body a . The portion 15 c^{23} is made longer than the distance between the rim of body a and the top of the cover, so that when the receptacle is closed the portion c^{23} is in an oblique position. By turning the handle c^{21} downward the lever will tilt on the 20 rim of the body a at x^2 , and as the portion c^{23} is thus moved toward a vertical position the resistance-point y^2 will force the cover b from the body a . It will be evident that the power applied to the handle c^{21} will be augmented 25 at y^2 on the same principles as described in reference to lever C.

Fig. 7 represents a lever somewhat similar to that shown in Figs. 1 to 4; but in this case the lever is made of wire instead of flat material, and the handle c^{31} is shown as turned down against the side of the body a below the cover b . The operation is the same, the part c^{33} bearing on the rim of the body a and the portion c^{34} against the rim of the cover b .

From the foregoing it will be seen that my improved lever-opener is of very simple construction, as it may be made of one piece and without rivets or other special fulcrum-bearings. The lever is firmly secured to the box 35 by having a portion adapted to be clamped between the body and cover, and I do not 40

limit myself to any special manner of doing this nor to any particular relative position of the parts other than that the fulcrum and resistance points of the lever bear against two parts of a receptacle and the lever is held in operative position by the simple closing of those two parts.

I claim as my invention—

1. The combination with a receptacle and a cover fitting thereon, of a lever-opener comprising a portion lying within the receptacle, a portion lying between the receptacle and its cover, and a handle portion extending beyond the other portions substantially parallel with the surface of the receptacle.

2. The combination with a receptacle and a cover fitting thereon, of a lever-opener comprising a portion lying between the receptacle and its cover, a portion turned over the rim of the receptacle, another portion turned out under the rim of the cover, and a handle portion extending beyond the other portions substantially parallel with the surface of the receptacle in position for operation to open the receptacle.

3. The combination of a receptacle comprising a body and a cover, with a lever-opener partly inclosed and held between said body and cover when the receptacle is closed, said receptacle being provided with an offset in which the part of the lever between the body and cover of the receptacle may lie, to permit of a tight closure of the receptacle.

In testimony whereof I have signed my name to this specification in the presence of two subscribing witnesses.

NEWCOMB CLEVELAND.
